UNITED STATES PATENT OFFICE.

CHARLES AMIGUET, OF NEW YORK, N. Y., ASSIGNOR TO DUPLEXALITE CORPORATION,
OF NEW YORK, N. Y., A CORPORATION OF NEW YORK.

LIGHTING-FIXTURE.

1,371,015.

Specification of Letters Patent.

Patented Mar. 8, 1921.

Application filed April 18, 1919. Serial No. 291,014.

To all whom it may concern:

Be it known that I, CHARLES AMIGUET, a citizen of the United States, residing in the borough of Manhattan of the city of New York, in the State of New York, have invented certain new and useful Improvements in Lighting-Fixtures, of which the following is a specification, reference being had to the accompanying drawing, forming 10 a part hereof.

The object of this invention is the construction of a lighting fixture in which the outer surface of an upper opaque reflector sending light rays upward for reflection 15 downward by the ceiling or its equivalent, is illuminated by a lower translucent member. Hitherto in constructions of this type the outer surface of the opaque reflector is illuminated only by reflection from the walls 20 of the room and is, therefore, sometimes not sufficiently illuminated to prevent it from appearing as a dark object. It is the purpose of this invention to remedy this defect and to accomplish this purpose the translucent member is suspended at a distance below 25 the lower edge of the opaque reflector and is preferably extended outwardly beyond such lower edge, whereby rays of light from the source of light not only pass 30 through the translucent member but are in part reflected from the upper surface thereof upwardly and outwardly illuminating the outer surface of the opaque reflector so as to prevent it from appearing as a dark 35 object, while the reflected rays add also to the illumination of the ceiling and the upper portions of the walls of the room. It is contemplated that the proportions of the upper reflector and the lower plate are such 40 that the illuminated sides of the reflector shall not be concealed or hidden by the plate, that is that the plate shall not be of such size and shape as to surround the reflector. The invention will be more fully explained 45 hereinafter with reference to the accompanying drawing in which it is illustrated and in which—

Figure 1 is a view in vertical section of a lighting fixture which embodies the invention, the lamp and its support being shown 50 in elevation.

Fig. 2 is a top view of the fixture shown in Fig. 1.

Fig. 3 is a view similar to Fig. 1 but show-

ing a dished, translucent member in place of 55 the flat plate shown in Fig. 1.

The opaque reflector *a*, made of any suitable material and supported in any convenient manner, is open both at the top and at the bottom, at least so far as the passage of 60 light rays is concerned, and has generally a lower contracted portion and an upwardly flaring rim, the curvature of the sides being preferably of the type shown, the outer curve being concave in vertical elevation. The 65 shape may be varied to suit the conditions of use and the requirement of artistic effect. Below the opaque reflector *a* is supported a translucent member *b* which preferably has a diameter somewhat greater than the lower 70 end of the opaque reflector, extending outwardly beyond the edge thereof. This translucent member may be supported in any convenient manner. As shown in the drawing it is supported by a spindle *c* carried by a narrow bridge piece *d* which, in turn, may be supported by the opaque reflector.

In Fig. 1 of the drawing, the translucent member *b* is flat, but obviously it might be 80 concaved upwardly or dished, as shown at *b'* in Fig. 3.

As indicated by the broken lines in Fig. 1 some of the rays of light from the source, indicated at *e*, strike the upper surface of 85 the translucent member *b* and are thence reflected upwardly and outwardly so that the outer surface of the opaque reflector *a* is illuminated sufficiently to prevent it from appearing wholly dark except as it may be 90 faintly illuminated by reflection from the walls of the room; the outer as well as the inner surfaces of the reflector may be covered with a reflecting coating of paint or other material or may be composed of material in itself reflective of light to increase the reflective capacity of the outer surface of the reflector. The space by which the translucent member *b* is separated from the lower edge of the opaque reflector and its 100 extension outwardly beyond the edge will be determined by the conditions of use. It should be placed far enough below to permit the desired result to be attained and should be extended outwardly far enough 105 to prevent the source of light from being seen by any person in the room illuminated, but the plate member is not large enough to

screen the effectiveness of the outer surface of the reflector.

I claim as my invention:

1. A lighting fixture comprising an upwardly flaring outwardly concaved opaque reflector open at top and bottom to rays of light, and a translucent member spaced apart from the lower edge of the reflector and extending beyond the lower edge but within the diameter of the upper opening of the reflector, the translucent member being adapted to reflect a portion of the light striking it to the exterior of the reflector.
2. A lighting fixture comprising a light

source, a fixture support, an upwardly flaring outwardly concaved reflector open at top and bottom to rays of light and reflective of light on both surfaces, and a translucent member spaced apart from the lower edge of the reflector but within the diameter of the upper opening of the reflector, such member being adapted to reflect a portion of the light striking it to the exterior of the reflector.

This specification signed this 19th day of March, A. D. 1919.

CHARLES AMIGUET.
